TYPEWRITING MACHINE

Henry Allen Avery, Groton, N. Y., assignor to
 L. C. Smith & Corona Typewriters, Inc., Syra-
 cuse, N. Y., a corporation of New York

Application June 28, 1934, Serial No. 732,865

11 Claims. (Cl. 197—88)

This invention relates to typewriting machines and like machines having a traveling carriage and escapement mechanism for the carriage.

The principal objects of the invention are to provide a simple, inexpensive and silently operating escapement mechanism; to provide a silently operating escapement mechanism of the type known as a reverse escapement in which substantially all of the letter space feed of the carriage occurs on the down strokes of the keys; and to provide an escapement which will silently control the feed of the carriage in letter spacing direction and is so constructed as to permit silent return of the carriage without releasing the carriage from the escapement.

To these ends, and to other ends which will appear from the following description in detail of a preferred embodiment of the invention shown in the accompanying drawing, the invention consists in the combinations of devices, features of construction, and arrangements of parts pointed out in the appended claims and set forth in the following description.

In the drawing:

Fig. 1 is a sectional view on the line 1—1 of Fig. 2;

Fig. 2 is a fragmentary top plan view of the machine, certain parts being broken away to more clearly show the improvements, and parts of the escapement being shown in normal position;

Fig. 3 is a side elevation of the escapement mechanism showing the dog rocker rocked from normal position to disengage the holding dog from the escapement wheel and engage the stepping dog with said wheel;

Fig. 4 is a bottom plan view of the escapement with the parts in normal position as in Figs. 1 and 2; and

Fig. 5 is a bottom plan view of the escapement with the dog rocker rocked as in Fig. 3 and the stepping dog holding the carriage arrested.

In the accompanying drawing the invention is shown embodied in a well known typewriting machine, only so much of which machine is illustrated as is necessary for a full understanding of the invention.

The platen carriage 10 carries a platen 11 and travels transversely of the machine on a carriage bed 12 which forms a part of the stationary framework of the machine, suitable ball bearings 13 being confined in raceways formed on the carriage and bed. A shaft 14 extends through a clearance aperture in the bed and is journaled at its upper and lower ends in a bracket 15 fixed to the bed. A feed pinion 16 is fixed on shaft 14

and meshes with a feed rack 17 held to the carriage to travel with the carriage. A toothed escapement wheel or circular escapement rack 18 is fixed on shaft 14 below the bed. The carriage is normally urged in letter spacing direction toward the left hand side of the machine by the usual spring drum and draw band, not shown.

At the rear of the escapement wheel is a sheet metal dog rocker 19 having a flat body portion and two pendant side arms. The side arms of the dog rocker are journaled on horizontal pivots 20 carried by the bracket 15. A dog rocker return spring 21, connected with rocker 19 and bracket 15, normally holds a stop edge 22 of one of the side arms of the rocker rocked down upon a stop lug 23 on bracket 15. The rocker is rocked, on the down strokes of the keys, upward and rearward from the position shown in Figs. 1 and 2 to that shown in Fig. 3 by a suitable universal bar mechanism, not shown. The improvements will now be described.

A flat sheet metal dog carrier 24 lies flatwise on the flat upper face of the main body portion of the dog rocker. This dog carrier extends fore-and-aft of the machine and is held to the dog rocker by an upstanding pivot bolt 25 having a nut 26 screwed on its lower end. The dog carrier is pivoted intermediate its forward and rear ends to provide a forward dog carrying end and a rear end which bears on the dog rocker to assist in preventing canting of the carrier relatively to the rocker; the forward or dog-carrying portion of the dog carrier overhanging a recess 27 in the forward edge of the dog rocker. Swinging movement of the dog carrier 24 on its pivot 25 in either direction is yieldingly resisted by two opposed coiled spring 28 which extend transversely of the machine. Lugs 29 on the dog rocker extend inwardly from opposite sides of recess 27 into the outer ends of springs 28, and lugs 30 on the dog carrier 24 extend outwardly from the forward end of the dog carrier at opposite sides of said carrier into the inner ends of the springs, the springs being held in place by the lugs and the dog carrier being held balanced in the position shown in the several views by the two opposed springs 28.

The holding dog 31 is pivotally held to the forward end of the dog carrier 24 at the upper face of the carrier by an upstanding pivot bolt 32, having a cylindrical nut 33 screwed on its lower end below the dog carrier. Holding dog 31 has a nose 34 forward of its pivot, which nose is normally engaged with a tooth of the escapement wheel, and said dog has a portion 35 in rear of

its pivot normally held rocked against a stop stud 36 fixed to the forward portion of the dog carrier. A light spring 37 connected to one side arm of the dog rocker and to the dog 31 forward 5 of the dog pivot normally holds part 35 of the dog against stud 36.

The stepping dog 38 is pivotally held at its rear end to and below the forward end of the dog carrier by an upstanding pivot bolt 39 which has 10 a nut 40 screwed thereon above the dog carrier. Stepping dog 38 has a nose 41 at its forward end, which nose is normally disengaged from the teeth of wheel 18 and held rocked toward the right of the wheel tooth engaged by dog 31 by means of 15 a light spring 42 connected to one side arm of the dog rocker and to the dog 38 forward of the pivot of said dog. Extending forward from the pivoted end of dog 38 at the left-hand side of the dog is a stiff spring finger 43 normally spaced to 20 the right of nut 33 but engageable with said nut when the stepping dog is rocked toward the left side of the machine.

On the down stroke of a type key or of the space bar of the machine the dog rocker 19 is rocked 25 upward and rearward by the usual universal bar mechanism from the position shown in Figs. 1 and 2 to that shown in Fig. 3, thus disengaging the tooth of wheel 18 held by dog 31 from said dog and positioning the nose of dog 38 in the 30 path of the next following tooth of the wheel, which following tooth engages the nose 41 of dog 38 and rocks said dog on its pivot against the pull of the light spring 42, causing the stiff spring finger 43 of dog 38 to engage nut 33 which 35 acts as a stop for the dog 38. The stiff spring finger cushions and silences the impact of the dog against its stop. It yields only very minutely and practically instantaneously brings dog 38 to rest with this dog positioned as shown in Fig. 5 40 relatively to dog 31 and the dog carrier 24, in which position the carriage has substantially completed a single letter space movement, the tooth-engaging edge of the nose of dog 38 being very slightly offset toward the right-hand side of 45 the machine relatively to the tooth-engaging edge of the nose of dog 31. The shock of arresting the aforesaid movement of the carriage is further cushioned, and the setting up of noise-producing vibrations and their transmission to the dog rock- 50 er and the stationary framework of the machine is further prevented, by the momentary yielding of the dog carrier 24 under the impact of finger 43 against stop nut 33. The dog carrier oscillates slightly on its pivot 25 under this impact but this 55 oscillation lasts only for an infinitesimal period, the dog carrier being brought substantially instantaneously to rest in its normally balanced position (shown most clearly in Figs. 2, 4 and 5) by the opposed balancing and centering springs 28 which 60 absorb the shock of arresting the carriage, the escapement parts assuming the position shown in Fig. 5 on the down stroke of a type key or space bar. On the up stroke of a type key or space bar the dog rocker is returned by spring 21, dog 38 65 is disengaged from the tooth by which it holds wheel 18, and the wheel turns slightly until this tooth is caught and held by the nose of holding dog 31 thus completing the single letter space movement of the carriage. The shock of arrest- 70 ing the carriage by dog 31 is absorbed and silenced by the momentary yielding or oscillation of dog carrier 24 as in the case of the shock of arresting the carriage by dog 38.

The carriage may be returned without releas- 75 ing the escapement, since the teeth of wheel 18

act as cams on holding dog 31 to swing the dog on its pivot 32 against the pull of spring 37 to permit the wheel teeth to pass the dog. The pivoted spring-balanced dog carrier absorbs the vibrations due to impact of part 35 of dog 31 on stop stud 36 as the teeth of wheel 18 pass the dog during return movement of the carriage.

The pivoted and spring balanced dog carrier also permits yielding of holding dog 31 under se- 10 vere thrusts or impacts on the carriage in the direction of letter feed travel of the carriage, thus preventing injury to the holding dog under such thrusts or impacts or when the machine is turned over on its left hand side.

What I claim is:

1. A typewriting or like machine having a carriage-feeding escapement wherein a dog rocker supports two dogs which co-act alternatively with a toothed element to feed a carriage step-by-step, characterized in that the dogs are carried 20 by a dog carrier which is mounted on the dog rocker to partake of the rocking movement of the rocker and also to yield relatively to the rocker under impacts of the teeth of the toothed element against the dogs.

2. A typewriting or like machine having a carriage traveling on a frame and an escapement for the carriage, characterized in that said escapement comprises a toothed element which moves when the carriage moves, a dog rocker sup- 30 ported to oscillate about a fixed axis on the frame, a dog carrier supported on the dog rocker to rock therewith about said axis and to swing relatively to the rocker about an axis extending transverse- 35 ly of the rocker axis, means for yieldingly re- 35 sisting swinging of the dog carrier about the axis which extends transversely of the rocker axis, and a pair of dogs carried by the dog carrier and co-active with the teeth of said toothed element to feed the carriage step by step when the dog 40 rocker is rocked.

3. A typewriting or like machine according to claim 1, characterized in that one of said dogs is a holding dog which is normally engaged with said toothed element and is pivoted on the dog 45 carrier for ratcheting thereover of the teeth of said toothed element during return movement of the carriage, and the other dog is a stepping dog which is pivoted on the dog carrier and normally disengaged from said toothed element.

4. In a typewriting machine having a frame and a carriage traveling on the frame, a carriage escapement for letter-feeding the carriage comprising a toothed element which moves when the carriage travels, a dog rocker supported on the frame to rock about a fixed axis, a dog carrier pivoted on the dog rocker to swing about an axis extending transversely of said fixed axis, means yieldingly resisting swinging of the carrier in either direction about the second-men- 60 tioned axis, a holding dog and a stepping dog each pivotally held to the dog carrier to swing about an axis parallel to the second-mentioned axis, means normally holding the dog rocker in a position in which the holding dog is engaged 65 with the toothed element and the stepping dog is disengaged from the toothed element, a holding dog stop on the dog carrier normally engaged by the holding dog and away from which said dog may be swung by the teeth of said toothed 70 element during return movement of the carriage, a spring normally holding the holding dog to its stop, a stepping dog stop on the dog carrier, and a spring normally holding the stepping dog rocked away from its stop.

5. In a typewriting machine having a frame and a carriage traveling on the frame, a carriage escapement for letter-feeding the carriage comprising a toothed element which moves when the carriage travels, a dog rocker supported on the frame to rock about a fixed axis, a dog carrier pivoted on the dog rocker to swing about an axis extending transversely of said fixed axis, means 5 yieldingly resisting swinging of the carrier in either direction about the second-mentioned axis, a holding dog and a stepping dog each pivotally held to the dog carrier to swing about an axis parallel to the second-mentioned axis, means normally holding the dog rocker in a position in which the holding dog is engaged with the toothed element and the stepping dog is disengaged from the toothed element, a holding dog stop on the dog carrier normally engaged by the holding dog and away from which said dog may be swung by the teeth of said toothed element during return movement of the carriage, a spring normally holding the holding dog to its stop, a stepping dog stop on the dog carrier, and a spring normally holding the stepping dog rocked away from its stop, said stepping dog having a resilient portion engageable with its stop when the stepping dog is rocked about its pivot by said toothed element in letter-feeding the carriage.
6. In a typewriting or like machine having a frame and a carriage traveling on the frame, a carriage escapement for feeding the carriage step-by-step in one direction comprising a toothed element which moves when the carriage moves in said direction, a pivotally supported dog rocker, dogs co-active with the teeth of said toothed element to feed the carriage in said direction when the rocker is rocked about its pivotal axis, and a dog carrier upon which said dogs are mounted and which is supported on the dog rocker to rock with the rocker and to yield relatively to the rocker under impacts of the teeth of the toothed element upon the dogs.
7. In a typewriting or like machine having a frame and a carriage traveling on the frame, a carriage escapement for feeding the carriage step-by-step in one direction comprising a toothed element which moves when the carriage moves in said direction, a pivotally supported dog rocker, dogs co-active with the teeth of said toothed element to feed the carriage in said direction when the rocker is rocked about its pivotal axis, a dog carrier upon which said dogs are mounted and which is supported on the dog rocker to rock therewith when the rocker is rocked and to shift relatively thereto under impacts of the teeth of the toothed element upon the dogs, and opposed spring means for yieldingly resisting shifting movement of the dog carrier relatively to the rocker and normally holding the carrier balanced therebetween in predetermined relation with the rocker.
8. In a typewriting or like machine having a frame and a carriage traveling on the frame, a carriage escapement for feeding the carriage step by step in one direction comprising a toothed element which moves when the carriage moves in said direction, a pivotally supported dog rocker, dogs co-active with the teeth of said
- toothed element to feed the carriage in said direction when the rocker is rocked about its pivotal axis, and a dog carrier upon which said dogs are mounted and which is pivotally held to the rocker to swing relatively to the rocker under impacts of the teeth of the toothed element upon the dogs, and spring means for yieldingly resisting swinging of the dog carrier relatively to the rocker.
9. In a typewriting or like machine having a frame and a platen carriage which travels transversely of the frame, the combination of a toothed element which moves when the carriage moves in one direction, feed dogs co-active alternately with the teeth of said element to feed the carriage in said direction, a dog rocker oscillatable about an axis fixed relatively to said element to cause said dogs to alternatively engage with the teeth of said element, a dog carrier pivoted on said rocker to swing about an axis 15 extending transversely of the rocker axis and carrying said dogs, and spring means yieldingly resisting swinging of said dog carrier in either direction about said second-mentioned axis and adapted to restore said carrier to one and the same relative position with respect to the dog rocker with either of said dogs engaged with a tooth of said toothed element.
10. In a typewriting machine having a frame and a platen carriage which travels transversely of the frame, the combination of a toothed element which moves when the carriage travels in one direction, feed dogs co-active alternately with the teeth of said element to feed the carriage step by step in said one direction, a dog 30 rocker oscillatable about an axis fixed with respect to said element, a dog carrier upon one end of which said dogs are mounted and which is pivoted intermediate its ends on the dog rocker to swing under impacts of teeth of said element upon the dogs, said carrier having its other end swingable over and in contact with a flat face of said rocker, and spring means for yieldably holding said carrier swung about its axis in predetermined relation with said rocker 40 when either dog is engaged with a tooth of said toothed element.
11. In a typewriting or like machine having a traveling carriage, an escapement mechanism for the carriage comprising a toothed element 50 which moves when the carriage travels in one direction, a dog rocker pivotally supported to swing relatively to said element about a fixed axis and in a fixed plane, a dog carrier pivoted on the rocker to swing under impacts of teeth of said element upon dogs carried by said rocker, a holding and a stepping dog carried by the dog carrier, and means for yieldably holding the dog carrier in a predetermined relation with the dog rocker and restoring the dog carrier into said relation after impact of a tooth of said element with either dog and while the dog is still engaged therewith, said dogs being alternatively engageable by teeth of said element to feed the carriage step-by-step in said one direction as 55 the rocker is rocked.

HENRY ALLEN AVERY.
